UNITED STATES PATENT OFFICE

100,422

DESIGN FOR A COMBINATION CABINET OR SIMILAR ARTICLE

Lozaire E. Gilbert, Springfield, Mass.

Application May 29, 1936, Serial No. 62,907

Term of patent 14 years

To all whom it may concern:

Be it known that I, Lozaire E. Gilbert, a citizen of the United States, residing at Springfield, in the county of Hampden and State of Massachusetts, have invented a new, original, and ornamental Design for a Combination Cabinet or Similar Article, of which the following is a specification, reference being had to the accompanying drawing, forming part thereof.

bination cabinet or similar article, showing my new design.

I claim:

The ornamental design for a combination cabinet or similar article, as shown.

LOZAIRE E. GILBERT.
